UNITED STATES PATENT OFFICE.

ELIZABETH B. BUNNELL, OF TOPEKA, KANSAS.

DESIGN FOR A GARMENT-SUPPORTER.

SPECIFICATION forming part of Design No. 25,795, dated July 21, 1896.

Application filed June 1, 1896. Serial No. 593,924. Term of patent 7 years.

To all whom it may concern:

Be it known that I, ELIZABETH B. BUNNELL, a citizen of the United States, residing at Topeka, in the county of Shawnee and State of Kansas, have invented a certain new and useful Design for Garment-Supporters; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 This invention relates to a certain new and useful design for a garment-supporting buckle or pin, such as may be used to retain in place a lady's shirt-waist, skirt, and belt, covering the meeting edges of skirt and waist.

20 The essential features of the design reside in the provision of a horizontal bar carrying midway its length an ornamental hook, which, when the article is applied to the garments, as in use, is the only part of the device which is visible.

25 I have clearly illustrated my design in the accompanying drawings, in which I have shown a perspective view of the front of the device embodying my design in Figure 1, and

in Fig. 2 I have shown a rear elevation of the 30 same.

Referring to the details of the design by letter, the pin or article embodying my design consists of the rectangular horizontal portion A, having at each end downwardly-projecting end portions B, having their upper and lower ends curved, as seen at C. Midway of the length of the bar A a hooked portion D rises vertically, and is bent forward upon itself, with the edges of the downwardly-extending portion laterally curved to the points d. The outline of the said downwardly-turned end is continued across its bottom in substantially a bow shape, and the front face of the downwardly-extended portion of the hook D 45 is ornamented with a scrollwork, as illustrated.

Having thus described my invention, what I claim to be new, and desire to secure by Letters Patent, is—

The design for a garment-supporter, substantially as shown and described.

In testimony whereof I affix my signature in presence of two witnesses.

ELIZABETH B. BUNNELL.
